UNITED STATES PATENT OFFICE.

CHARLES E. JOHNSON, OF PHILADELPHIA, PENNSYLVANIA.

HEAT CONCENTRATING AND DEFLECTING DEVICE.

1,366,806.

Specification of Letters Patent. Patented Jan. 25, 1921.

Application filed November 1, 1919. Serial No. 335,024.

To all whom it may concern:

Be it known that I, CHARLES E. JOHNSON, a subject of the King of Great Britain, residing at Philadelphia, in the county of 5 Philadelphia and State of Pennsylvania, have invented new and useful Improvements in Heat Concentrating and Deflecting Devices, of which the following is a specification.

10 The invention relates to stoves and ranges and has for an object to provide a device for use in connection with a stove or range, for concentrating the heat beneath a particular lid or vessel, or deflecting the heat 15 from a point beneath the device to an adjacent pot or vessel receiving opening of the stove.

My device is particularly adapted for use in connection with domestic stoves and 20 ranges and particularly in kitchen stoves, whether they be gas or coal stoves and to this end I provide a simple device which is arranged to depend in one of the openings in the stove top and has suitable means for 25 bringing about a concentration of the heat beneath the particular opening in which it is placed or for deflecting the heat to an adjacent opening in the stove top.

In the further disclosure of the invention, 30 reference is to be had to the accompanying drawings constituting a part of this specification in which similar characters of reference denote corresponding parts in all the views, and in which,—

35 Figure 1—is a perspective view of the device by itself.

Fig. 2—is a vertical sectional view taken through the device showing the arrangement of one of the pintles.

40 Fig. 3—is a side elevation of the operating member or key, and

Fig. 4—is a plan view of a stove top showing the opening with one of my devices positioned to show the manner of guiding 45 or deflecting the heat to the openings.

Referring more particularly to the views, I provide a substantially circular body 10 formed to provide an upper horizontal circular rim 11 and a substantially semi-circular 50 depending wall 12, which is so disposed as to the rim 11, to provide an annular flange 13 formed by the periphery of the rim 11 and which may be also termed the outer edge of the rim, whereas the inner edge of the 55 rim forming an opening 14 has a projecting ledge 15 for a purpose which will be here-

inafter more clearly described. The semi-circular wall 12 has each end cut away as at 16 and is formed with a longitudinally apertured circular bearing head or hinge element 17. Between the ends of the wall 12 there depends from the underside of the rim 11, a support 18 which also forms a wall and which is provided with opposed cut away portions 19 and projecting longitudinal apertured circular bearing heads or 60 hinges 20. With this intermediate support 18 it will be seen that a plurality of adjacent passages 21 are provided and these are normally closed by doors or swinging 65 members 22, each consisting of a slightly curved plate 23 formed with a longitudinally apertured circular hinge element 24. A pair of the doors 22 are provided for 70 each passage 21 and one of the doors in each pair is hinged to one of the hinge elements 20 by having its hinge element 24 projecting into the cut away portion 19 with a suitable operating pin 25 in the nature of a 75 pintle provided to swingingly support the door in position, the other door being of course mounted upon one of the hinge elements 17 and having its hinge element 24 extending into the cut away portion 16, one of the operating pins or pintles 25 being employed for the hinging of each door. Each 80 door has a squared depression 26 in the upper end of the hinge element 24 thereof and the body 19 in the rim 11 is provided with openings 27 registering with the 85 depressions 26 so that a key 28, including a squared end 29 and handle 30, can be arranged to have its squared end 29 pass through one of the openings 27 and extend into the squared depression adjacent 90 the opening so that a swinging movement 95 can be imparted to the door or doors to open or close the same.

A stove top is indicated by the numeral 31 and is provided with openings 32 which 100 are bordered by flanges 33 forming seats so that when one of the devices described is disposed in one of the openings, the flanges 33 will rest upon the seat 33, thus positioning the device in the opening of the stove 105 top. A suitable lid for the circular body 10 can be provided, the lid being indicated by the numeral 34, and when in position is adapted to close the opening 14, resting upon the ledge 15. It will be seen, by reference 110 to the views that each door has a stop lug 35 formed with its hinge element to engage

the face of the wall 12 or support 18, as the case may be, to limit the opening movements of the doors.

Now it will be seen that when all of the doors are closed that the wall 12 which normally is semi-circular, will through the medium of the closed doors and the interposed support 18 form a continuous circular wall which, depending beneath the stove top 10 and close to the source of heat, will tend to confine the heat beneath the lid or cooking vessel which may be placed upon the body 10, or upon the stove top over the opening 14. When it is desired to deflect a portion 15 of the heat to the adjacent opening of the stove top, and which may or may not be provided with one of the devices, it is only necessary to swing certain or all of the doors into positions whereby the passages 21 will be 20 opened so that the heat which rises within the wall 12 will be deflected by the superposed cooking vessel or lid and passing through the open passage or passages, will be guided toward the adjacent opening, over 25 which a cooking vessel has been disposed, containing probably a food which is to be subjected to a slight heating action to bring about a simmering of the contents of this vessel.

30 It will of course be understood that the device described can be used in connection with various forms of stoves and ranges and

can be operated as desired to deflect or guide the heat from one opening toward the other or concentrate the heat beneath one of the 35 openings over which a lid or cooking vessel has been placed and although I have shown a particular form of my invention in the drawings and described the specific construction thereof in this specification, it will 40 be clear that various slight changes can be made without departing from the spirit of the invention, the scope of which is defined in the appended claim.

Having described my invention, I claim— 45

A device of the class described comprising a horizontally disposed annulus, an annular wall depending from the underside thereof and including a fixed section and movable sections mounted for swinging 50 movement, said annulus having openings therein arranged above the pivot end of said swinging sections, said pivot ends being provided with squared recesses and adapted to receive a tool for moving the sections to 55 open and closed positions, said sections normally forming a continuation of the said wall and the inner periphery of said annulus being offset to provide a ledge disposed within the confines of the said annular 60 wall for the purpose specified.

In testimony whereof I affix my signature.

CHARLES E. JOHNSON.
